[57] CLAIM

The ornamental design for a fence supportable decoration or similar article, as shown and described.

DESCRIPTION

FIG. 1 is a perspective view of a fence supportable decoration or similar article showing my new design;
FIG. 2 is an edge elevational view of the head portion taken on line 2—2 of FIG. 1;
FIG. 3 is an edge elevational view taken on line 3—3 of FIG. 1; and
FIG. 4 is a rear elevational view.

The decoration or similar article is a face and pair of hands; adapted to be supported on a fence which does not comprise any part of the disclosure.

FIG. 1

FIG. 4
